UNITED STATES PATENT OFFICE

HOWARD G. ALLEN, OF NIAGARA FALLS, NEW YORK, ASSIGNOR TO H. R. BLISS COMPANY, INC., OF NIAGARA FALLS, NEW YORK, A CORPORATION OF NEW YORK

FEEDING AND SPACING DEVICE

Application filed August 2, 1928. Serial No. 296,889.

This invention has to do with a device for feeding articles as regards a machine which performs operations upon the articles and in which the feeding of the articles is rendered intermittent so that the operations can be performed at spaced points upon the articles between the intermittent movements. In this regard the apparatus of this invention may be operably associated with the machine for performing the operations so as to act in unison therewith. The invention also contemplates a construction in which some of the intermittent movements of the articles fed thereby may be varied so that the operations performed thereon may be irregularly located as regards the articles where such irregular location of the operations are desired. More specifically, the invention is concerned with a feeding device which is useful in feeding container or box blanks of fibre board past the stitcher head of a wire stitching machine. The intermittent movements given to the blanks cause the stitches to be spaced apart so that a row of stitches may be effected. At the ends of a row of stitches it is sometimes desirable, to make an especially strong container, to have double stitches, or in other words, two stitches located in close proximity. Accordingly the invention contemplates a controllable mechanism for varying or tripping the feed movements for effecting this double stitch formation.

In the accompanying drawings:

Fig. 1 is a side view of the apparatus illustrating the mechanism for effecting intermittent feeding.

Fig. 2 is a view similar to Fig. 1 illustrating the intermittent feeding mechanism in another position.

Fig. 3 is a side view of the device taken from the side opposite that of Figs. 1 and 2 illustrating the structure for effecting variation in the feeding distance of some of the intermittent movements of the articles to be fed.

Fig. 4 is a top plan view of the device illustrating a clutch construction which is open to effect variation in the length of the feed movement.

Fig. 5 is a similar view illustrating the clutch in closed position.

Fig. 6 is a section taken substantially on line 6—6 of Fig. 4.

Fig. 7 is a detail of one of the lever arms 55 which is associated in the structure for effecting intermittent feeding.

Fig. 8 is a section taken on line 8—8 of Fig. 7 illustrating the adjustment of the lever of Fig. 7.

Fig. 9 is an assembly view somewhat diagrammatically illustrating the device of the invention associated with a stitching machine.

Fig. 10 is an end view of the same.

Figs. 11 and 12 are views showing two fibre board members of the container stitched together and illustrating the double stitch at the end of the row of stitches.

There is shown in Figs. 9 and 10 of the drawings attached hereto a wire stitching machine 1 having a stitching head 2 which may be driven by a suitable source of power, as for example electric motor 3. The stitching machine has a drive shaft 4 equipped 70 with a gear wheel 5 in mesh with gear 6 on the motor shaft. A suitable spool of wire is shown at 7. A detailed description of the stitching mechanism is not necessary inasmuch as the invention herein is concerned 75 only with a feeding mechanism which is useful for any sort of stitching machine or the like, it being sufficient to say that positioned below the stitcher head is an anvil 8 and that the articles to be stitched together, 80 which may be two fibre board blanks 9 and 10, are disposed between the stitcher head and anvil.

As the stitching machine operates it will be appreciated that a row of stitches in the blanks 9 and 10 will be effected as these blanks are fed along underneath the stitcher head, and for this purpose an intermittent feeding is necessary to provide periods of rest while the stitcher head is throwing the 95 stitch.

In Fig. 11 the two blanks 9 and 10 are shown secured together by a row of stitches 11, and for the purpose of reinforcing the container to be formed there is an extra 100

stitch 12 at each end relatively close to the next adjoining stitch, thus forming double stitches. It will therefore be seen that to effect the regular spaced stitches in a row, a regular intermittent movement of the feeding of the blanks is necessary, but that this regular intermittent feeding must be varied or tripped to effect the double stitches 12.

Associated with the stitcher are feeding 10 rollers, some of which, as for example 15 and 16, may be idlers, while 17 and 18 are driven inasmuch as the two are connected together by a belt 19, and roller 18 is mounted upon a drive shaft 20 carrying sprocket 21 driven by chain 22. Chain 22 runs over driving sprocket 23.

This driving sprocket 23 is rotated by suitable power means preferably through the means of chain 24, (Figs. 9 and 10) passing 20 over a sprocket 25 on shaft 4. Gear 5 and sprocket 25 may be keyed together and both mounted to freely rotate upon the end of the shaft 4, the purpose of which will later be brought out.

25 Chain 24 drives the sprocket 23 through a speed changing device. This device includes a sprocket 26 (Figs. 1 and 9) which may be mounted upon shaft 27 together with pulleys 28 over which runs a belt 29 with the belt also running over pulleys 30 and shaft 31 in turn equipped with a sprocket 32. The speed changing construction may be one of a number of types which are available on the market, and the pulleys 28 and 30 are arranged for adjustment to vary their effective diameter where they are engaged by belt 29 thus to change the relative speeds between shaft 27 and shaft 31. This may be accomplished by an adjusting wheel 33 which may be equipped with a chain 34 which runs over the sprocket equipped with a crank handle (not shown). Details of this variable speed mechanism are not shown and are not essential inasmuch as the same is well understood by those versed in the art.

50 A chain 35 passes over sprocket 32 and passes over sprocket 36 in shaft 37 (Fig. 1) which also carries a sprocket 38. Chain 39 runs over sprocket 38 and a sprocket 40 on shaft 41, and on this shaft 41 sprocket 23 is secured.

Accordingly, it will be seen that the driving motor drives the feed sprocket 23 through the several sprocket and chain connections shown with the speed changing device interposed. Accordingly the speed of the sprocket 23 may be varied thus to in turn vary the speed of the advancing movement of the blanks 9 and 10 as regards the stitcher head. With the stitching machine operating at a given uniform rate, the distance between stitches in a row may be varied by increasing or decreasing the feed 60 movement of the blanks by adjustment of

the speed changing device, which will be explained later.

It will be appreciated that a stitching machine throws stitches with successive operations with an intervening lapse of time occurring between each stitch throwing movement. Accordingly, it is desirable that the blanks be fed with an intermittent movement so that the blanks are stationary at the time a stitch is thrown and so that it moves during the intervening time between stitches. This is effected by providing a chain 39 with slack, as shown, and alternately releasing and taking up the slack as the chain runs over sprockets 38 and 40. There are 75 two idler sprockets 45 and 46 which engage chain 39, and these sprockets are carried respectively upon levers 47 and 48. These levers are pivoted midway of their length, as shown. The opposite ends of these levers 80 are associated with a double cam 49 having cam groove 50 and cam groove 51, and each lever may have a roller 52 and 53 for engagement in the cam groove. Preferably, closed cams are used as shown, although 85 open cams with spring devices for keeping the rollers in contact with the surface may be used if desired.

This cam device is mounted on shaft 55 which also carries sprocket 56 (Fig. 4) by 90 means of which the shaft is driven. As shown in Figs. 9 and 10 chain 57 runs over sprocket 56 which in turn runs over sprocket 58 on shaft 59, which has a sprocket 60, with a chain 61 running over this sprocket 100 and sprocket 62 on the stitcher shaft 4. The sprocket 62 is suitably keyed to the shaft 4 but as above pointed out gear 5 rotates on the shaft whereby the shaft and sprocket 62 may remain idle while the motor is running.

A suitable clutch is positioned between sprocket 5 and sprocket 62 which includes a sleeve 63 slidable on the shaft and slidably pinned to sprocket 5. This sleeve has a groove 64 within which there is engaged a cam operating member 65. This cam is on a rock shaft 66, and on its opposite end is a lever 67 carrying roller 68 which is adapted to be engaged by the blanks which are to be stitched. As the blanks are fed to the machine they ride under roller 68 thus rocking shaft 66 and actuating cam 65 to slide the clutch sleeve 63 which has a clutching engagement with gear 62 as shown. Accordingly, the motor and gear 5 and all other parts operably connected to gear 5 may run continuously, whereas the stitching head and the sprocket 62 and all other parts operating from sprocket 62 are operated only when the clutch is engaged. The form of clutch here shown is a simple one for the purpose of exemplification and other forms of clutch devices may be used.

110 It will be seen, therefore, that at the be- 130

ginning of an operation, the motor may be started and that gear 5 and sprocket 25 may rotate continuously, and this continuously drives the feeding rollers 15 to 18 inclusive, 5 it being understood that these feeding rollers have been properly adjusted for the speed of feeding by means of the speed changing device interposed between the rollers and the motor. The clutch is normally disengaged 10 and thus the stitching machine and the sprocket 62 do not rotate. Accordingly, the cam 49 does not rotate and the chain 39 merely runs past the idler sprockets 45 and 46.

15 When the clutch is engaged, as by means of blanks 9 and 10 raising the roller 68, the cam 49 is set into motion thus rocking the levers 47 and 48.

When this cam is operating these two levers are actuated so that the idlers 45 and 46 approach each other in one movement and move away from each other in the next movement. The approximate extreme inward and outward positions of the idlers 45 and 25 46 are shown in Figs. 1 and 2. It will be observed by reference to these figures, that these idlers alternately take up and release slack on alternate sides of the chain 39.

Assuming that the arms with the idler 30 sprockets 45 and 46 are in any given position, as for example, the position shown in Fig. 2, and the motor is running with the clutch disengaged, the shaft 41 rotates with an even continuous movement which corresponds 35 with the continuous rotation of sprocket 38. This moves the feeding rollers 15 to 18 inclusive, with an even continuous movement.

However, upon rotation of the cam 49 the lever 47 moves from the position of Fig. 2 40 to the position of Fig. 1 thus taking up chain coming from gear 38. Viewing Figs. 1 and 2, the gears 38 and 40 rotate clock-wise. Simultaneously with this, the idler 46 moves upwardly toward idler 45 thus releasing 45 slack in the chain. Accordingly, at this time the sprocket 40, and accordingly sprocket 23, and the feeding rollers remain idle as the chain, which is moving over sprocket 38, is given up by idler 46 and taken up by idler 50 45. Upon continued rotation, however, idler 45 moves back from the position shown in Fig. 1 to that shown in Fig. 2 whereas idler 46 also moves back from the position shown in Fig. 1 to that shown in Fig. 2. Accordingly 55 idler 46 takes up chain while idler 45 releases slack in the chain. Thus the shaft 41 is rotated during this movement of the levers.

Inasmuch as the same amount of chain 60 which moves over sprocket 38 must move over sprocket 40, the sprocket 40 moves with the greater speed than sprocket 38 when the idlers are moved from the position shown in Fig. 1 to the position shown in Fig. 2. Thus 65 while sprocket 40 is idle in one movement

of the levers, it moves at a higher rate of speed than sprocket 38 at the other movement of the levers, and the same amount of chain passes the sprockets 38 and 40 in any given cycle of movement.

This intermittent movement of the sprocket 40 feeds the blank feeding rollers with like intermittent movement so that the blanks are fed intermittently with periods of rest. When the clutch is thrown in the stitcher 70 head 2 is also thrown into operative engagement and the stitcher head and cam 49 operate in unison so that the blanks, which are being stitched, are stationary during the throwing of a stitch. In the interval between the throwing of successive stitches the blanks move forwardly and come to rest again at the time when another stitch is to be placed in the blanks.

In order that a nicety of adjustment may be had in the chain 39, the lever 47 may be made double, as shown in Figs. 7 and 8, with the two parts pivoted independently on fulcrum pin 47a and connected by an adjusting screw 47b and set screw 47c. Accordingly, 80 it will be observed that by adjusting screw 47b that the angularity of the two lever parts may be varied and the proper adjustment may be maintained by the set screw 47c.

As thus far described, the stitches in the 95 row will be uniformly spaced as the apparatus is in operation, as indicated by the stitches 11 in Figs. 11 and 12. However, the feeding movement is tripped at proper times for effecting double stitches, as at 12. For 100 this purpose (see Figs. 4 and 5) sprocket 23 is loosely mounted on shaft 41 and is provided with a clutch member 70. A cooperating clutch member in the form of a sleeve 71 is 105 slidably keyed to the shaft and is backed up by a spring 72 normally tending to keep the two clutch members 70 and 71 in engagement. For operating the clutch sleeve the same may be grooved, as at 73, and a lever 74 has studs 75 engaging in this groove (Figs. 3 and 9). This lever is pivoted, as at 76, and has one end 77 in engagement with the cam 78 (Fig. 5) mounted on shaft 55. This shaft 55, as will be remembered, rotates continuously with cam 49 when the stitching machine 110 is in operation, and only when the clutch is engaged. Accordingly as the shaft 55 rotates the cam 78 tends to swing lever 74 on its fulcrum point and disengage the two clutch members to prevent rotation of the feeding sprocket 23. However, the shaft 55 makes one rotation for each spacing between each two stitches, and it is desirable to disengage the clutch members 70 and 71 between only some of the stitches and not all of them.

To prevent disengagement of the clutch members 70 and 71 in each feeding movement, the fulcrum pin 76 is carried by a slide 80 acted upon by a spring 81 (Figs. 4, 5, 6). The spring 72 is stronger than the spring 81 130

and when the cam 78 tends to rock lever 74 in counterclockwise direction, viewing Fig. 5, the spring 81 is extended thus permitting the movement of the fulcrum point 76 instead of movement of the end of the lever 74, which is in engagement with the clutch member 71. Means are provided, however, for blocking this movement of the slide 80 at certain feeding movements in order to keep 10 the fulcrum point 76 fixed whereby the rocking of the lever moves clutch member 71 to open position thus compressing spring 72.

This blocking means may take the form of a chain 85 running over an idler sprocket 86, 15 and the sprocket is advanced with step by step movement by means of a crank 87 associated with shaft 55 and carrying a spring pressed pawl 88. Accordingly, on each rotation of shaft 55 the idler sprocket 86 is advanced one step. Carried by this chain 85 are a number of blocks 89. As shown in Fig. 6 the slide 80 carries an adjusting screw 90 which is arranged to abut against blocks 89.

It will be seen therefore that in the normal 25 operation of the structure there is no block 89 positioned adjacent the screw 90 and the clutch members 70 and 71 remain in engagement and the blanks are fed to form a row of 30 stitches with the stitches evenly spaced apart. This is because the spring 81 gives instead of 35 spring 72 thus permitting the fulcrum point to move by reason of the slide 80. When one of the blocks 89 takes the position as shown in Figs. 3 and 6 the slide is prevented from movement and thus the clutch members 70 and 71 are disengaged so that the feed driving sprocket 23 is not actuated.

However slight spacing is desired between 40 the double stitches 12 and accordingly there must be some movement of the feed sprocket 23. Accordingly when the feed movement begins at the time when the double stitch is required, the slide is blocked and thus the clutch is opened and there is no feeding 45 movement. However, at this time the idler sprocket 86 is moved by the dog 88 and the blocks are of such a length as to release the slide near the end of the feeding movement inasmuch as the block moves out from behind 50 the screw 90. This action occurs preferably after the cam 78 has been released from the lever arm 74. Preferably the arrangement is such at this time that the tooth members of the clutches 70 and 71 come together end 55 to end as the slide is released. As the clutch member 71 is rotated, its teeth slip into engagement with the teeth of the member 70. This permits members 70 and 71 to engage under action of the spring 72 so that in the 60 last portion of the feeding stroke the blanks are fed forwardly.

For example, the slide may be blocked for approximately three-quarters of the feeding stroke, and then the clutch members 70 and 65 71 permitted to engage during the last

quarter of the stroke. For further example, to give a more concrete idea, the stitches 11 may be spaced, say two inches apart, but where a double stitch is required the feeding movement is blocked for three-quarters 70 of the movement; thus the double stitches are spaced approximately one half an inch apart.

It will be understood that the blocks 89 on the chain 85 are so positioned as to form double stitches where the double stitch is required. In a larger container where the row of stitches is longer, the blocks will be spaced farther apart in order to form double stitches at the end of the row. A number of different chains may be kept on hand and 80 the chains may be alternately used on the apparatus to readily adapt the machine for stitching containers of different sizes. Of course the blocks can be arranged so that a double stitch may be had at any point along 85 the length of stitches if for any reason the same be desirable.

The controlling of the step by step or intermittent feeding of the blanks to be 90 stitched by means of the slack chain construction wherein the slack is alternately absorbed and then given up by the idler sprockets, is advantageous because of its positive manner of operation. The slack in the chain is positively controlled by the cam 95 which runs in unison with the stitching machine and there is no overrunning or varying of the distance between the stitches inasmuch as the feeding sprocket 23 is controlled directly by the chain, as distinguished 100 from a feeding device employing a ratchet and pawl construction wherein there is much chance for overrunning variation.

Moreover, the trip mechanism for effecting 105 the double stitches is advantageous in that it is also very positive in its action, and also because of the ease in which the trip mechanism may be varied to accommodate the entire apparatus for making different 110 stitch arrangements, as is required in containers of different sizes. The only thing required to change over the machine from one size container to another is by merely placing a different block carrying chain on sprocket 86, and a number of these can be on 115 hand ready for use. The distance between stitches in a row can be regulated by the speed variation drive.

What I claim is:

1. The combination with a wire stitching 120 machine, of means having normally a uniform movement for feeding articles to be stitched past the stitching mechanism, and means acting in unison with the stitching mechanism and acting upon the feeding means so as to translate the feeding movement into an intermittent movement with 125 periods of rest in the movement, the stitching machine and the said means acting in unison therewith being so timed that the 130

stitching mechanism actuates during the periods of rest of the intermittent movement.

2. The combination with a wire stitching machine, of means having uniform movement for feeding articles to be stitched past the stitching mechanism, means acting in unison with the stitching mechanism and acting upon the feeding means so as to translate the feeding movement into an intermittent movement with periods of rest in the movement, the stitching machine and the said means acting in unison therewith being so timed that the stitching mechanism actuates during the periods of rest of the intermittent movement, and variable speed means for varying the speed of feeding whereby to effect variation in the distance between successive stitches.
3. The combination with a wire stitching machine, of power means for the stitching machine, feeding means for feeding articles past the stitching machine, said feeding means being connected with the power means to continuously actuate therewith, and means for translating the movement of the articles imparted by the feeding means into an intermittent movement, a clutch device positioned between the power means and both the stitching mechanism and translating means, and means for closing the clutch as the articles are advanced to the stitching mechanism.
4. The combination with a wire stitching machine, of power means for the stitching machine, feeding means for feeding articles past the stitching machine, said feeding means being connected with the power means to continuously actuate therewith, means for translating the movement of the articles imparted by the feeding means into an intermittent movement, a clutch device positioned between the power means and both the stitching mechanism and translating means, and means for closing the clutch as the articles are advanced to the stitching mechanism.
5. The combination of a power operated rotary element, a second rotary element through which the power is communicated, flexible means running over the two rotary elements, said flexible means being relatively loosely associated with the two rotary elements, and means for alternately taking up and releasing slack in the flexible means whereby a substantially even rotary movement of the first element effects intermittent movement of the second element.
6. The combination of a rotating sprocket, a second rotating sprocket, a loose chain running over the sprockets, said first sprocket

driving the second, and means for alternately absorbing and giving up slack in the chain whereby a substantially even rotary movement of the first sprocket effects an intermittent rotary movement of the second sprocket.

7. The combination of a rotary sprocket, a second sprocket, a loose chain running over the sprockets, a pair of pivoted levers, idler sprockets on each lever engaging opposite sides of the loose chain, and means for rocking the levers whereby slack in the chain is alternately taken up and released by the idler sprockets to effect an intermittent movement of the second mentioned sprocket.

8. The combination of a rotary sprocket, a second sprocket, a loose chain running over the sprockets whereby the first drives the second, a pair of levers each having an idler sprocket associated with opposite sides of the loose chain, and means for rocking the levers so that the idler sprockets alternately absorb and give up slack in the chain whereby a substantially even rotary movement of the first sprocket effects an intermittent movement of the second sprocket.

9. In a feeding mechanism, the combination of an intermittently rotating element, means for imparting movement to this element including a positive two way clutch, and means for opening the clutch at determined intermittent movements of the element for effecting variation of the rotary motion of said element at the determined movement.

10. In a feeding device for feeding an article with an intermittent movement, the combination of an intermittently rotating feeding element, means for actuating the element including a clutch, a clutch actuating lever, a movable fulcrum pin for the lever, means for rocking the lever, and means for holding the movable fulcrum pin stationary at determined times to effect rocking of the lever upon its fulcrum pin to open said clutch.

11. In a feeding device for feeding an article with an intermittent movement, the combination of an intermittently rotating feeding element, means for rotating this element including a clutch, a spring normally closing the clutch, a lever associated with the clutch, a movable fulcrum pin for the lever, means actuating the lever during the intermittent movements of the feeding element which moves the said fulcrum pin, and means for blocking the fulcrum pin from movement at determined times whereby the lever is rocked thereon to open said clutch.

12. In a feeding device for feeding an article with an intermittent movement, the combination with an intermittently movable feeding element, means for moving said element including a clutch, a spring normally closing the clutch, a movable slide, a spring acting upon this slide, a lever fulcrumed upon the slide and associated with the clutch, means acting upon the lever at the inter-

mittent movements of the feeding element, said second named spring being relatively weak as compared to the first whereby said second named spring actuates to permit movement of the slide with the clutch remaining closed, and means for blocking the movement of the slide at determined times whereby the lever rocks upon its fulcrum to open the said clutch.

13. In a feeding device for feeding an article with an intermittent movement, the combination with an intermittently movable feeding element, means for moving said element including a clutch, a spring normally closing the clutch, a movable slide, a spring acting upon this slide, a lever fulcrumed upon the slide and associated with the clutch, means acting upon the lever at the intermittent movements of the feeding element, said second named spring being relatively weak as compared to the first whereby said second named spring actuates to permit movement of the slide with the clutch remaining closed, and means for blocking the movement of the slide at determined times whereby the lever rocks upon its fulcrum to open the said clutch, said means being in the form of a rotary element having a series of spaced blocks successively coming into blocking position as regards the slide.

14. In a feeding device for feeding an article with an intermittent movement, the combination with an intermittently movable feeding element, means for moving said element including a clutch, a movable slide, a spring normally closing the clutch, a lever fulcrumed upon the slide and associated with the clutch, means acting upon the lever at the intermittent movements of the feeding element, said second named spring being relatively weak as compared to the first whereby said second named spring actuates to permit movement of the slide with the clutch remaining closed, means for locking the movement of the slide at determined times whereby the lever rocks upon its fulcrum to open the said clutch, said means including a sprocket, a chain running over the sprocket, and blocks on the chain which are successively brought into blocking relation as regards the slide.

15. In a feeding device for feeding an article with an intermittent movement, the combination with an intermittently movable feeding element, means for moving said element including a clutch, a spring normally closing the clutch, a movable slide, a spring acting upon this slide, a lever fulcrumed upon the slide and associated with the clutch, means acting upon the lever at the intermittent movements of the feeding element, said second named spring being relatively weak as compared to the first whereby said second named spring actuates to permit movement of the slide with the clutch remaining closed.

means for locking the movement of the slide at determined times whereby the lever rocks upon its fulcrum to open the said clutch, said means including a sprocket, a chain running over the sprocket, blocks on the chain which are successively brought into blocking relation as regards the slide, and an adjustable abutment on the slide for engaging the blocks.

16. In a feeding means for feeding an article to be stitched past a stitching machine with intermittent movements of the articles so that a row of stitches are placed in the article, the combination of an intermittently operating feeding means, a loose chain running over a sprocket, a series of blocks on the chain, and means for rotating this sprocket so that the blocks are brought successively into blocking relation as regards the intermittent feeding means whereby to vary the feeding movement at determined intervals to effect double stitches at these intervals.

In testimony whereof I affix my signature.

HOWARD G. ALLEN.
